UNITED STATES PATENT OFFICE

159,794

PROJECTION UNIT FOR A METALLO-
GRAPHIC MICROSCOPE

Bernhardt George Gallasch, Rochester, N. Y., assignor to Bausch & Lomb Optical Company, Rochester, N. Y., a corporation of New York

Application December 3, 1949, Serial No. 6,402

Term of patent 14 years

(Cl. D57—1)

To all whom it may concern:

Be it known that I, Bernhardt George Gallasch, a citizen of the United States and a resident of Rochester, county of Monroe, and State of New York, have invented a new, original, and ornamental Design for Projection Unit for a Metallographic Microscope, of which the following is a specification, reference being had to the accompanying drawing, forming a part hereof.

Fig. 1 is a perspective view showing the right front side of a projection unit for a metallographic microscope embodying my new design.

Fig. 2 is a perspective view of the left front side thereof.

Fig. 3 is a rear view thereof.

The essential features of my design are shown in full lines, the showing of the eye pieces in broken lines in Fig. 2 has been omitted from Fig. 1 for convenience of illustration and the

broken line showings of a supporting base in Figs. 1 and 2 are omitted from Fig. 3 for convenience of illustration.

I claim:

The ornamental design for a projection unit for a metallographic microscope, substantially as shown and described.

BERNHARDT GEORGE GALLASCH.
